CIGAR LIGHTER OR SIMILAR ARTICLE

Kenyon William James Jones, London, England, assignor
to Ronson Corporation, Newark, N. J., a corporation
of New Jersey

Application October 3, 1956, Serial No. 43,224

Claims priority, application Great Britain June 1, 1956
Term of patent 14 years

(Cl. D48—27)

Fig. 1.

Fig. 2.

Fig. 3.

Fig. 1 is a front elevation of a cigar lighter embodying my new design;

Figs. 2 and 3 are, respectively, a top plan view and perspective view of such cigar lighter.

The characteristic feature of my design for the cigar lighter disclosed resides in the upper beaded windguard having the configuration shown.

I claim:

The ornamental design for a cigar lighter or similar article, substantially as shown and described.
